UNITED STATES PATENT OFFICE.

SAMUEL L. WESTERFIELD, OF NEW YORK, N. Y.

DESIGN FOR A CORAL BOOK-STAND.

Specification forming part of Design No. 6,280, dated November 26, 1872.

To all whom it may concern:

Be it known that I, SAMUEL L. WESTERFIELD, of the city, county, and State of New York, have invented a Design for a Coral Book-Stand, of which the following is a specification:

The nature of my design is fully represented in the accompanying drawing, to which reference is made, and of which—

Figure 1 is an elevation; Fig. 2, a top view; and Fig. 3, a section on line *x x*.

The leaf A of the stand has staff and star projections C D on its face and periphery. The legs E, which support the leaf, curve outward at the base and inward at the leaf, and are or-

namented with staffs or projections F F, and are united by a secondary leaf, G, having staff and star projections C D. The whole is coated with cement, and the coral pressed on—or, instead of the coral, rice may be pressed on the cement and afterward painted red—giving the stand a rustic, yet neat and ornamental, appearance.

What I claim as new, and desire to secure by Letters Patent, is—

The design, shown and described.

SAMUEL L. WESTERFIELD.
